US00D900812S

(12) **United States Design Patent** (10) Patent No.: **US D900,812 S**
(45) Date of Patent: ** Nov. 3, 2020

(54) **USER INTERFACE DEVICE**

(71) Applicant: **Flint Rehabilitation Devices, LLC**,
Irvine, CA (US)

(72) Inventors: **Nizan Friedman**, Irvine, CA (US);
Daniel K. Zondervan, Long Beach,
CA (US)

(73) Assignee: **FLINT REHABILITATION
DEVICES, LLC**, Irvine, CA (US)

(**) Term: **15 Years**

(21) Appl. No.: **29/646,463**

(22) Filed: **May 4, 2018**

(51) LOC (12) Cl. **14-02**

(52) U.S. Cl.

(57) **CLAIM**

The ornamental design for a user interface device, as shown and described.

DESCRIPTION

FIG. 1 is a top perspective view of a user interface device showing our new design;

FIG. 2 is a first lateral side view thereof;

FIG. 3 is a second lateral side view thereof;

FIG. 4 is a third lateral side view thereof;

FIG. 5 is a fourth lateral side view thereof;

FIG. 6 is a top view thereof; and,

FIG. 7 is a bottom view thereof.

The broken lines in the drawings depict portions of the user interface device that form no part of the claimed design.

1 Claim, 5 Drawing Sheets
